United States Patent Office

Des. 200,933
Patented Apr. 20, 1965

200,933

PENCIL BOX

George Reiner, 225 E. 70th St., New York, N.Y.

Filed Nov. 19, 1963, Ser. No. 77,500

Term of patent 14 years

(Cl. D58—12)

FIG. 1

FIG. 4

FIG. 1 is a perspective view of a pencil box showing my new design,

FIG. 2 is a front elevational view thereof,

FIG. 3 is a side elevational view thereof partially in cross-section taken on line 3—3 of FIG. 2, the opposite side being a mirror image thereof; and

FIG. 4 is a rear elevational view thereof.

The essential features of my design reside in the portions shown in full lines.

I claim:

The ornamental design for a pencil box, as shown and described.
